Claims priority, application Great Britain Mar. 28, 1962
14 Claims. (Cl. 229—17)

This invention relates to containers and in particular to containers which include a body made of cardboard or similar material and are intended primarily to contain liquids.

Containers of this kind currently in use are usually coated with wax but this kind of container is expensive to produce because it is necessary to use a high quality cardboard and the cost of the wax and the application thereof to the container has considerably increased the cost. This kind of container does however lend itself to the formation of what has become known as a "gable" form of closure which is an attractive kind of closure and is capable of being provided with a pouring spout.

It has also been proposed to line a cardboard container with a bag of heat-sealable material, the bag being secured inside the collapsed outer cardboard carton to be set up simultaneously with the setting up of the carton. With such proposed forms of container, however, the mouth of the bag is heat-sealed and is then folded into the outer carton which is closed by folding closure flaps flat one over another and securing the outer flaps one to the other. Such a container does not possess the attractive appearance of the gable-closed container and does not lend itself to the provision of a pouring spout. Further, it is difficult to obtain access to the heat-sealed bag unless scissors are readily available.

It is a main object of the present invention to provide a container which consists of an outer carton made of relatively inexpensive cardboard or like material and which is lined with a bag made of heat-sealable liquid-impervious organic thermoplastic material, and which is capable of being provided with means for effecting opening of the heat-sealed bag.

According to the invention there is provided a container comprising a carton made of cardboard or similar material and having a body the interior of which is lined by a bag made of heat-sealable liquid-impervious organic thermoplastic material extending outwards from the top of the carton body and having the mouth thereof closed by a seam formed by the juxtaposition and heat-sealing of two opposite side portions of the bag, the side portions of the bag which extend between said seam and the top of the carton body being covered by cover flaps which slope towards each other from opposite sides of the top of the carton body and which terminate in seam-engaging flaps provided with tearing edges located between the longitudinal edges of the seam-engaging flaps and extending from positions adjacent to like ends of the seam-engaging flaps towards the opposite ends of the flaps and with lines of weakening which extend from the free longitudinal edges of the seam-engaging flaps towards the tearing edges at positions intermediate the opposite ends of the flaps, said tearing edges being spaced by like distances from the free longitudinal edges of the seam-engaging flaps and the seam-engaging flaps being secured to said juxtaposed opposite side portions of the bag except in regions thereof located between said tearing edges and the free longitudinal edges of the seam-engaging flaps thereby to facilitate tearing of the bag along said tearing edges following tearing thereof along a path defined by said lines of weakening while gripped between the seam-engaging flap portions located on opposite sides of the lines of weakening.

2

In order that the invention may be clearly understood some embodiments thereof will now be described, by way of example, with reference to the accompanying drawings, in which:

5 FIGURE 1 illustrates a blank for carton according to the invention,

FIGURE 2 illustrates the container in a partly set-up condition thereof,

FIGURE 3 illustrates a container according to the invention,

10 FIGURE 4 illustrates, in exaggerated form, the mode of closing the mouth of the bag,

FIGURE 5 illustrates the manner of opening the sealed bag,

15 FIGURE 6 illustrates the manner in which a pouring spout is formed,

FIGURE 7 illustrates a blank for an alternative form of carton according to the invention,

20 FIGURE 8 illustrates the mouth end of the carton formed from the blank shown in FIG. 7,

FIGURE 9 illustrates the manner of opening the sealed bag of the carton of FIG. 8, and

25 FIGURES 10 and 11 illustrate further alternative forms of carton according to the invention.

In the drawings like reference numerals indicate like or similar parts.

Referring to the drawings, FIGURE 1 illustrates a blank made of cardboard or similar material from which a carton is made. The blank has four body-forming sides 1, 2, 3, 4 and a flap 5 which, when the blank is folded to form a four-sided body is secured, as by an adhesive, to the side 1. At one end of the blank are four bottom-closing flaps 6, 7, 8, 9 which when the container is set up are folded flat one over the other in known manner, 30 the outer flaps being secured, as by an adhesive, one to the other.

The opposite end of the blank is provided with two rectangular cover flaps 10, 11 which in the set-up condition of the container extend from opposite sides at the top 12, FIG. 3, of the body and with two triangular end flaps 13, 14 which are independent of the cover flaps 10, 11 and have the bases thereof hinged to the top 12 of the carton body. In the set-up condition of the carton, FIG. 3 the end flaps 13, 14 slope towards each other. 40

45 The cover flaps 10, 11 have seam-engaging flaps 15, 16 formed in extension thereof and these flaps are connected by a pourer-forming flap 17 and a connecting flap 18. The flaps 17, 18 are respectively provided with medial creases 19, 20 about which they can be folded as described below.

50 The seam-engaging flaps 15, 16 are each provided with a line of weakening, formed by a series of closely adjacent short slits 21, which extends from the free longitudinal edge 22 of the flap towards and substantially to the junction 23 of the flap with its cover flap. An opening 24 is formed in each seam-engaging flap 15, 16 at a position between the free longitudinal edge 22 and junction 23 and presents a tearing edge 25. As shown in the drawings, the upper edge of the opening 24 is spaced from the tearing edge 25 at a position which is between the tearing edge 25 and the free longitudinal edge of the seam-engaging flap. The tearing edge 25 is located between the longitudinal edges 22, 23 of the seam-engaging flaps 15, 16 and extends from positions adjacent to the like ends 26, 27 of the seam-engaging flaps towards the opposite ends 28, 29 of the flaps. The edge 25 is an edge along which, as is described below, bag material can be torn following tearing thereof together with the seam-forming flap along the line of weakening 21 and the edges 25 in the seam-engaging flaps 15, 16 are spaced by like distances from the free longitudinal edges 22 of the said flaps. Preferably the

tearing edge 25 is substantially at right angles to the line of weakening 21.

The pourer-forming flap 17 is provided with openings 30, similar to the openings 24, and the openings 30, when the container is closed as illustrated in FIGURE 4, are alignable with the openings 24.

A bag 31, FIGURE 2, lines the carton and has a closed end 32. The bag is made of heat-sealable liquid-impervious material, preferably an organic thermoplastic material such as polyethylene, and is preferably made from a seamless tube. The bag is so located in the carton that the mouth end of the bag extends outwards from the top of the carton body and the bag is preferably secured to the body so that it is set up simultaneously with the setting up of the carton body.

Following the closing of the bottom of the carton by the bottom flaps 6, 7, 8, 9 and the insertion of the contents into the bag, the mouth of the bag is closed by infolding of the end flaps 10, 11 and 13, 14. This causes the formation of a mouth-closing seam formed by the juxtaposition of the two opposite side portions 33, 34 and the gusset-folding, FIGURE 4, of the other side portions 35, 36, the gusset folds being disposed between the juxtaposed portions 33, 34 and folded together with the flaps 17, 18 which are folded about the medial creases 19, 20 formed therein. In this condition, as illustrated in FIGURE 3, the sides of the bag extending between the seam and the top of the carton body and which terminate in said opposite side portions 33, 34 are covered and engaged by the cover flaps 10, 11 which slope towards each other from the tops of the opposite sides 1, 3 of the carton body. The side portions 35, 36 of the mouth end of the bag are engaged by the triangular end flaps 13, 14 which also slope towards each other from the tops of the opposite sides 2, 4 of the carton body.

The seam-engaging flaps 15, 16 are secured, as by adhesive, to the bag portions 33, 34, FIGURE 2, and although flaps 17, 18 need not be secured to the bag portions 35, 36 in the preferred embodiment of the invention they are so secured.

In the closed condition thereof the mouth portion of the bag extends beyond the free longitudinal edges 22 of the seam-engaging flaps 15, 16 and is sealed by a heat-induced bead seal 37, FIGURE 3. The sealing is effected by a bead seal because of the thickness of the seam which for most of the length thereof consists of four thicknesses of bag material but at the centre of the seam consists, for a short distance, of only two thicknesses of bag material. The bead seal ensures a completely liquid-tight seal which could not be ensured by a bar seal.

When it is desired to obtain access to the contents of the container the portion 38 is gripped between a finger and thumb of one hand and, with the other hand, the lines of weakening 21 are torn from the edges 22 down to the junction 23. The lines of weakening are located in the region of the bead seal which consists of only two thicknesses of bag material and this eases the tearing of the bag material and results in tearing of the seam-engaging flaps 15, 16 and of the bag material secured thereto and so presents raw edges of bag material for tearing along the tearing edges 25. This is effected by gripping the portions 39 between the finger and thumb of one hand and the portion 40 with the other hand and then tearing the bag material along the tearing edges 25 towards the ends 26, 27 of the seam-engaging flaps 15, 16 and completely removing the portion 40, FIGURE 3. From the drawings it will be observed that the bag portions 41 which cover the openings 24, 30 are located between the tearing edges 25 and the free longitudinal edges of the seam-engaging flaps and are not secured to the seam-engaging flaps. It has been found to be essential to the tearing of the bag material that the portion thereof immediately above the tearing

edges 25 be free to stretch in order to effect tearing thereof and it is for this reason that the said portions of the bag material are arranged to be unsecured to the seam-engaging flaps.

The bag is now opened and by pulling out the infolded pourer-forming flap 17, FIGURE 6, the bag portion secured thereto is caused to form a pouring spout 42. If desired, to facilitate the pulling out of the flap 17 the latter may be provided with a tag 43 as indicated in broken lines in FIGURES 1 and 6.

FIGURES 7 to 9 illustrate an alternative form of carton embodying the invention and from FIGURE 7 it will be seen that the blank is generally similar to that of FIGURE 1 but that the bottom end flaps 6, 7, 8 and 9 are designed to be connected by infolding and interlocking, instead of by adhesive, and that the triangular flaps 13, 14 are not independent of the cover flaps 10, 11 but are connected thereto by portions 44 through slit and tag connections 45. Further, the tearing edges 25 are formed by slits, instead of openings, made in the seam-engaging flaps 15, 16 and pourer-forming flaps 17 and the lines of weakening 26 are formed by slits which extend from edge 22 nearly, but not quite, to the slits forming the tearing edges 25. In FIGURE 7 adhesive is indicated by hatching and it will be noted that no adhesive is applied to the area 45 so that the bag portions immediately above the tearing edges 25 are not adhered to the seam-engaging flaps 15, 16 or to the pourer-forming flap 17.

The alternative carton shown in FIGURE 10 is similar to that of FIGURE 8 but carton sides 2 and 4 are provided with crease lines 47 which permit the mouth end of the carton to be closed in a manner such that the bag mouth-closing seam consists of only two juxtaposed opposite portions throughout the whole length thereof. This permits the heat-sealing of the bag mouth-closing seam by a sealing device of well known form and which is known as a band sealer.

The carton shown in FIGURE 11 is similar to that of FIGURE 10 except that the crease lines 47 commence at positions intermediate the bottom and top of the carton body so that the lower portion 48 of the carton body is of rectangular cross-section similar to that of the cartons shown in FIGURES 3 and 8.

I claim:

1. A carton made of cardboard or similar material comprising a body, the interior of which is lined by a bag made of heat-sealable liquid-impervious organic thermoplastic material, said bag extending outwards from the top of the carton body and having the mouth thereof closed by a seam formed by the juxtaposition and heat-sealing of two opposite side portions of the bag, cover flaps connected one to each of two opposite sides of the body at the top thereof, said cover flaps sloping towards each other and covering the side portions of the bag which extend between said seam and the top of the carton body, and seam-engaging flaps extending one from each of the cover flaps and engaging said seam, said seam-engaging flaps including tearing edges located between the longitudinal edges of the seam-engaging flaps and extending from positions adjacent to like ends of the flaps towards the opposite ends thereof and lines of weakening which extend from the free longitudinal edges of the flaps towards the tearing edges at positions intermediate the opposite ends of the flaps, said tearing edges being spaced by like distances from the free longitudinal edges of the seam-engaging flaps and the seam-engaging flaps being secured to said juxtaposed opposite side portions of the bag except in regions thereof located between said tearing edges and the free longitudinal edges of the seam-engaging flaps thereby to facilitate tearing of the bag along said tearing edges following tearing thereof along a path defined by said lines of weakening while gripped between the seam-engaging flap portions located on opposite sides of the lines of weakening.

2. A carton according to claim 1, wherein each tearing edge is formed by one side of an opening formed in a seam-engaging flap and another side of the opening is spaced from said one side at a position between said one side and the free longitudinal edge of the seam-engaging flap.

3. A carton according to claim 1, wherein each tearing edge is substantially at right angles to the line of weakening extending towards said tearing edge.

4. A carton according to claim 3, wherein each line of weakening is formed by a series of closely adjacent slits.

5. A carton made of cardboard or similar material comprising a four-sided body the interior of which is lined by a bag made of heat-sealable liquid-impervious organic thermoplastic material, said bag extending outwards from the top of the carton body and having the mouth thereof closed by a seam formed by the juxtaposition and heat-sealing of two opposite side portions of the bag, cover flaps connected one to each of two opposite sides of the body at the top thereof, said cover flaps sloping towards each other and covering the side portions of the bag which extend between said seam and the top of the carton body, seam-engaging flaps extending one from each of the cover flaps and engaging said seam, a connecting flap connecting one pair of like ends of the seam-engaging flaps and provided with a medial crease, and a pourer-forming flap connecting the other pair of like ends of the seam-engaging flaps and provided with a medial crease about which it is foldable to form with portions of the bag a spout by which the contents of the carton may be poured therefrom, said seam-engaging flaps including tearing edges located between the longitudinal edges of the seam-engaging flaps and extending from positions adjacent to like ends of the flaps towards the opposite ends thereof and lines of weakening which extend from the free longitudinal edges of the flaps towards the tearing edges at positions intermediate the opposite ends of the flaps, said tearing edges being spaced by like distances from the free longitudinal edges of the seam-engaging flaps and the seam-engaging flaps being secured to said juxtaposed opposite side portions of the bag except in regions thereof located between said tearing edges and the free longitudinal edges of the seam-engaging flaps thereby to facilitate tearing of the bag along said tearing edges following tearing thereof along a path defined by said lines of weakening while gripped between the seam-engaging flap portions located on opposite sides of the lines of weakening.

6. A carton according to claim 5 wherein the connecting flap and the pourer-forming flap are each secured to the bag.

50

7. A carton according to claim 6, wherein the connecting flap and the pourer-forming flap and the sides of the bag associated therewith are gusset-folded to form said seam and the pourer-forming flap is provided with a tearing edge aligned with the tearing edges formed in the seam-engaging flaps.

8. A carton according to claim 5, wherein the connecting flap and the pourer-forming flap and the sides of the bag associated therewith are gusset-folded to form said seam and the pourer-forming flap is provided with a tearing edge aligned with the tearing edges formed in the seam-engaging flaps.

9. A carton according to claim 5, wherein each tearing edge is formed by one side of an opening formed in a seam-engaging flap and another side of the opening is spaced from said one side at a position between said one side and the free longitudinal edge of the seam-engaging flap.

10. A carton according to claim 5, wherein each tearing edge is substantially at right angles to the line of weakening extending toward said tearing edge.

11. A carton according to claim 10, wherein each line of weakening is formed by a series of closely adjacent slits.

12. A carton according to claim 7, wherein each tearing edge is formed by one side of an opening formed in a seam-engaging flap and another side of the opening is spaced from said one side at a position between said one side and the free longitudinal edge of the seam-engaging flap.

13. A carton according to claim 12, wherein each tearing edge is substantially at right angles to the line of weakening extending towards said tearing edge.

14. A carton according to claim 13, wherein each line of weakening is formed by a series of closely adjacent slits.
